CLAIM

The ornamental design for a sidewall of a tire with graphic symbol, as shown and described.

DESCRIPTION

FIG. 1 is an enlarged view of the graphic symbol removed from the sidewall for clarity of illustration; and, FIG. 2 is a front view of a sidewall of a tire with graphic symbol shown in an environment of use. The dashed lines in the drawing are shown for environmental purposes only and form no part of the claimed design. The dash-dot broken lines define the bounds of the claimed design and form no part thereof.
